RELAY

Edwin O. Blodgett, Rochester, N. Y., assignor to
General Railway Signal Company, Rochester,
N. Y.

Application July 28, 1934, Serial No. 737,440

24 Claims. (Cl. 246—41)

This invention relates to relays, and more particularly to a tractive type relay which is self-compensating to allow its armature to be released from its attracted position in response to an abrupt decrease in energization of the relay with the same certainty regardless of the degree of energization which had gradually obtained previously.

In a normally energized track circuit, it is essential to attract the armature of the track relay associated therewith and to hold the armature in its attracted position during normally unoccupied conditions from current passing through the rails of the insulating section of track in series, but when the section becomes occupied, the train must shunt sufficient current through the wheels and axles to effect the release of the relay armature. Obviously, then, the leakage of the current from one rail to the other throughout the track section affects the armature of the track relay in the same manner as the shunt effected by a train, and consequently it is found that when the track circuit current is adjusted to a value permitting proper operation at any one time, a change in weather condition may in one instance sufficiently increase the current leakage between rails to duplicate the effect of a train shunt and drop the usual type of track relay, or in another instance the leakage current may sufficiently decrease to increase the relay energization to such an abnormally high value that the relay armature will not release in response to a train shunt.

In view of the above and other considerations, it is proposed in accordance with the present invention to provide a self-compensating relay particularly adapted to produce reliable operation under various special conditions, such as encountered in a track circuit, to which the conventional type of tractive relay is not particularly adapted. Specifically, it is proposed to provide a relay of the tractive armature type which is self-compensating to maintain a constant tractive force acting on its armature when in its attracted position regardless of changes which may occur gradually in the energization of the relay to thereby allow the armature to drop away in response to an abrupt reduction in energization with equal certainty regardless of the degree of energization which had previously obtained gradually. It is further proposed to provide a locking means actuated by a release of the armature to prevent the above compensating action as long as the armature is in its re-

leased position, and it is also proposed to incorporate a simple and reliable means for manually adjusting the magnitude of the armature retaining force which is to thus be maintained constant regardless of subsequent gradual variations in energization, and to provide such an adjustment which will not affect the magnitude of the force by which the armature is attracted from its released position. 5

Other objects, purposes and characteristic features of the present invention will be obvious as the description thereof progresses, during which, references will be made to the accompanying drawings, in which—

Fig. 1 diagrammatically shows a preferred form 15 of the present invention applied to a normally energized railway track circuit.

Fig. 2 is a front elevational sectional view of a relay incorporating a preferred embodiment of 20 the present invention.

Fig. 3 is a side elevational sectional view of the 25 relay shown in Fig. 2.

Fig. 4 is a partial bottom view of the relay 30 shown in Fig. 2 with the armature and certain other parts removed.

Fig. 5 is a plan view of a detail of the relay 35 shown in Fig. 2.

Fig. 6 is a partial front elevational sectional 40 view showing a modification which may be made in the relay shown in Fig. 2.

Fig. 7 is a side elevational view of a relay 45 incorporating a modified form of the present invention with certain parts of the relay sectioned and other parts removed.

Fig. 8 is a front elevational view of the relay 50 shown in Fig. 7, also having certain parts sectioned.

In the drawings, the present invention has been shown as applied to a relay constructed 40 along the lines of the type found suitable for railway signalling systems and particularly for railway track circuits, but it will be obvious that the present invention can equally well be applied to various other well known relay types. 45 The general construction of the relay shown in detail includes two vertical cores 7 and 8 having enlarged lower ends forming pole faces 9 and 10, respectively, whereby they are held to a top plate 11 by screws 12, the top plate 11 being of insulating or at least non-magnetic material. The cores 7 and 8 carry windings 13 and 14, respectively, which are normally connected in series and arranged to produce cumulative flux within the cores 7 and 8, which cores 55

are joined at their upper ends by a yoke 15 of magnetic material held thereto by bolts 16.

A tractive type magnetic armature 17 is pivotally supported below the lower surface of the 5 pole pieces 9 and 10 so as to be attracted thereto and complete the magnetic circuit by energization of the coils 13 and 14, the armature 17 being biased away from the pole pieces 9 and 10 by gravity. The armature supporting means comprises a non-magnetic yoke 18 (see Fig. 4) suspended from the top plate 11 by bolts 19 each attached to the top plate 11 by nuts 20 bearing on spacing bushings 21, the yoke 18 being carried between upper and lower nuts 22 to 10 thereby be vertically adjustable along the end portions of the bolts 19. Two armature arms 23 are suitably attached to the armature 17 and adjustably hold outwardly extending trunnion pins 25 by screws 26, which trunnion pins have 15 reduced ends rotatably fitting into holes in downwardly extending lugs 27 carried by the yoke 18. The armature 17 is thus adjustably supported to permit pivotal movement relative to the pole faces 9 and 10 with a minimum of friction.

Suitable contacts are, of course, attached to the armature 17 in a manner to engage either upper or lower fixed contacts in accordance with the operation of the armature, but to simplify the present disclosure such contact means have been omitted from all views, except Fig. 3 which shows in a very diagrammatic manner a movable contact finger 28 attached to the armature 17 by insulating spacing screws 29, and this 30 movable finger 28 engages either front or back fixed contacts indicated merely by the arrows in Fig. 3.

In a tractive type relay, such as just described, it is well known that the force retaining the armature in its attracted position against the pole pieces is substantially proportional to the flux 40 in the magnetic circuit, and consequently in certain relay applications, such as, a track circuit wherein it is desirable to maintain a constant armature retaining force when the track section 45 is unoccupied, it is desirable to maintain the flux in the magnetic circuit constant regardless of changes in inter-rail leakage current. A constant flux value can, of course, be maintained by an auxiliary means maintaining a constant value 50 of energization of the relay coils or the magnetomotive force of the relay but the present device does not act on the energizing circuit but rather, it acts on the magnetic circuit in a manner to maintain a constant flux value in the magnetic circuit by varying the reluctance thereof in inverse proportion to changes in the magnetomotive force which occur gradually, and yet allow the flux to decrease sufficiently in response 55 to abrupt changes in the magnetomotive force to release the armature.

Inasmuch as one factor determining the reluctance of the magnetic circuit is the air gap separating the armature from the pole faces, the present device is arranged to enforce a separation of the armature 17 from the pole faces 9 and 10 which is in inverse proportion to the magnetomotive force obtaining between these pole pieces 9 and 10. The preferred apparatus for effecting 60 such operation is shown in Figs. 2 to 5 inclusively, and comprises a vertical shaft 33 positioned midway between the cores 7 and 8 with its lower end rounded and engaging the upper surface of the armature 17 and its upper end threaded into 65 a bushing 34. The bushing 34 is shown as

threaded only at its upper end, the lower end forming a bearing for the shaft 33 and is provided with an annular upper flange retained in a recess in the top of the plate 11 by a cover plate 35 secured above the plate 11 by screws 36 5 as shown in Fig. 5.

The shaft 33 is rotated to various positions in accordance with the magnetomotive force obtaining between the pole pieces 9 and 10 by an armature 37 suitably attached thereto and having enlarged circular ends, these circular ends coacting with curved inner vertical surfaces of the pole pieces 9 and 10 as shown in Fig. 4, the armature 37 being shown in all the present figures as assuming a position in response to a 15 maximum value of magnetomotive force which would normally obtain in the relay. The armature 37 thus being separated by a small air gap from the vertical surface of the pole pieces 9 and 10 tends to rotate to a position aligning with the 20 flux flowing therethrough from one pole piece to the other, and of course, the armature 37 also tends to rotate to a position wherein the reluctance to the flow of such flux therethrough is a minimum or, that is, to place more of the 25 surface of its pole faces in register with the surface of the pole pieces 9 and 10, all of which is in accordance with well known principles of magnetic attraction.

Referring to Fig. 4 which is a view looking at 30 the lower end of the present relay with the armature 17 removed, the rotatable armature 37 is shown as rotated to its extreme position in a counter-clockwise direction against the biasing force of a spiral coil spring 38, which spring is 35 attached at its inner end to the top plate 11 by a stud 39, and at its other end to a sector 40 by a pin 41. The sector 40 is also attached to the shaft 33 at a point above the armature 37 and extends rearwardly for a purpose to be later described.

If the spring 38 is arranged to exert a force tending to rotate the shaft 33 in a clockwise direction which force increases evenly in direct proportion to the counter-clockwise rotation of 45 the shaft 33, the various values of magnetomotive force between the pole pieces 9 and 10 will effect a force counteracting the opposing force of the spring 38 only at certain definite rotated positions of the shaft 33. For example, when 50 the armature 37 is in the position shown, each decrement in the magnetomotive force produces a proportional degree of clockwise rotation of the shaft 33. Inasmuch as the upper end of the shaft 33 is provided with right-hand threads, 55 the shaft will now be moved upwardly within the stationary threaded bushing 34 due to this clockwise rotation, thereby allowing the armature 17 to move closer to the pole pieces 9 and 10.

This upward movement of the armature 17 as 60 permitted by the upward movement of the shaft 33 obviously decreases the air gap between the armature 17 and the pole pieces 9 and 10, thereby decreasing the reluctance of the magnetic circuit in direct proportion to the degree of reduction 65 in energization of the coils 13 and 14 as detected by the rotation of the armature 37. In this manner, the flux in the armature 17 and consequently the tractive force acting thereon is maintained at a constant value regardless of the decrease 70 in the magnetomotive force or the energization of the relay coils 13 and 14.

The converse action of the armature 37 is of course obvious, or that is, the shaft 33 will be rotated counterclockwise in response to a grad- 75

ual increase in magnetomotive force to thereby screw the shaft 33 downwardly within the bushing 34. This downward motion of the shaft increases the reluctance of the magnetic circuit by 5 forcing the armature 17 farther from the pole pieces 9 and 10 thereby preventing an increase of flux.

The pitch of the threads on the upper end of the shaft 33 will, of course, depend on the characteristics of the magnetic circuit and on the proportion of various other parts of the relay, but it is to be understood that these threads must be arranged to vary the air gap between the armature 17 and the pole pieces 9 and 10 in such 15 a proportion to a change in magnetomotive force that the flux in the armature 17 remains at a constant value.

It was previously mentioned that the armature 37 is to respond only to changes which occur 20 gradually in the magnetomotive force or the energization of coils 13 and 14, and the air gap should not be varied in response to an abrupt decrease in relay energization. This is because the 25 purpose of regulating the air gap is to allow the armature to at all times drop away with equal certainty when the energization is quickly reduced, and if the air gap were varied in response to this quick reduction before the armature dropped away, the benefit of the previous air gap 30 regulation would be lost.

Consequently, the armature 37 is provided with two flux retarding washers or slugs 43 of a non-magnetic current-conducting material, such as 35 copper, brass or aluminum, and these slugs 43 completely surround the armature 37 at positions between the shaft 33 and the respective enlarged ends or pole faces. An effective amount 40 of current is then induced in these washers 43 when the flux in the armature 37 tends to change quickly, which current acts to retard such change in flux in a manner which is well recognized in the relay art. These slugs 43 will then act to retard a rapid decrease in flux in the armature 37 45 in response to a rapidly reduced relay energization, thereby preventing an effective rotation of the armature 37 until the armature 17 has been released by the reduction of the flux permitted by the inaction of the armature 37. However, gradual changes in the relay energization or the 50 magnetomotive force will produce such a gradual flux change through the armature 37 that the flux retarding slugs 43 are practically ineffective, and the rotation of the armature 37 will follow very closely such gradual changes in magnetomotive 55 force.

It is to be understood, however, that although the armature 17 drops away before the armature 37 can respond to a rapidly reduced value of magnetomotive force, the armature 37 will subsequently respond to this reduced value by rotating to a position moving the shaft 33 downwardly. However, when the armature 17 is again attracted by a quickly increased value of magnetomotive force, the armature 37 will not 60 immediately rotate back to again raise the shaft 33, and during the operation of the armature 37 an air gap will be momentarily provided which is not proportional to the newly increased magnetomotive force.

70 In some applications such operation of the armature 37 while the armature 17 is released, may be objectionable, and consequently the present relay is provided with an upwardly extending spring arm 44 suitably attached to a rearwardly extending bracket 45 fixed to the arma-

ture 17 by screws 46 as shown in Fig. 3. The upper end of the spring arm 44 is positioned slightly to the rear of and out of engagement with the edges of the previously mentioned sector 40 when the armature 17 is attracted, but when the armature 17 is released, the spring arm 44 is operated forwardly to engage the edge of the sector 40 and thereby prevent further movement of the shaft 33 while the armature 17 is in its released position.

5 Inasmuch as it has been considered that the rotation of the shaft 33 will not be more than about one-fourth of a revolution, the sector 40 may have a quarter circular outer edge concentric with the shaft 33 as shown in Fig. 4, and the right-hand edge may form a stop for the biased 10 direction of rotation by engaging the downwardly extending head of the spring holding stud 39. The outer edge of the sector 40 may be 15 roughened or serrated to provide a better frictional contact with the spring arm 44.

The present device, of course, necessitates that the normal or average energization of the coils 20 13 and 14 be adjusted to a value which reliably 25 attracts the armature 17 from its deenergized position, and low enough to permit reasonably gradual variations either above or below this normal value to fall within the range of operation of the armature 37 in order to maintain a 30 constant flux in the armature 17. This constant armature flux must also be of a value which permits the most reliable armature release in response to the degree of abrupt reduction in the 35 energization of coils 13 and 14 which is effected in the particular circuit application.

However, it is found in certain applications, such as railway track circuits, that even though the normal or average energization of the relay coils is a correct value, the abrupt reductions in 40 energization may be of considerably different magnitudes in different track circuits, due perhaps to the different weights of trains shunting the track circuits, and the like. It then becomes 45 desirable that this constant flux value in the armature 17 be adjusted to a value providing proper armature release in response to the degree of the abrupt energy reduction resulting from the particular train shunts, providing such adjustment does not affect the degree of energization 50 required to pick up the armature.

A rather simple means has consequently been provided for manually adjusting the normal or average air gap between the pole pieces 9 and 10 and the armature 17 when attracted, to thereby 55 select a normal flux value in the armature 17 which provides the maximum reliability of response to the particular abrupt reduction of relay energization effected in each application. This means is shown in Fig. 5 as comprising a 60 pointer arm 48 extending forwardly from the flange of the bushing 34 and having a pointer at its front end cooperating with arcuate graduations suitably marked on the top plate 11. The arm 48 may be rotated in either direction from 65 its illustrated position thus rotating the bushing 34 relatively to the shaft 33 to either move the shaft 33 upwardly or downwardly to accordingly vary the air gap between the armature 17 and the pole pieces 9 and 10, and consequently vary 70 the normal value of flux in the armature 17. The adjusted position of the arm 48 may be retained by a screw 49 threaded into the top plate 11 and extending through a circular slot in the outer end of the arm 48.

In Fig. 6 of the drawings, the same relay as shown in Fig. 2 is illustrated as having windings 50 on the rotating armature 37 in addition to the non-magnetic current-conducting washers 43, 5 which washers in this case, are made shorter to provide space for the coils 50. The two windings 50 are shown as connected in series by a wire 51 and in multiple with the main windings 13 and 14 by wires 52, and these windings 50 are arranged 10 to produce cumulative flux in the armature 37, which flux is to flow in the same direction as the flux produced in the armature 37 by energization of coils 13 and 14. This arrangement in Fig. 6 substantially constitutes a shunt motor mechanism for rotating the shaft 33, wherein the windings 13 and 14 supply the field excitation coacting with the armature flux supplied by windings 50, and it is contemplated that additional torque tending to rotate the shaft 33 throughout its 90 20 degree rotation against the biasing spring 38 may thereby be provided. The washers 43 are intended to retard the response of the armature 37 to rapid changes in energization of the relay in the same manner as in Fig. 2.

The operation of the previously described form of the present relay may be more clearly set forth by referring to Fig. 1, in which a very diagrammatic representation of the preferred form of the present invention is shown connected across one 30 end of two track rails T, the other rail ends being connected to a battery B in series with a manually adjustable resistor R to thereby normally energize the windings of the present relay by current from the battery B flowing through the track rails T 35 in series. The parts of the present relay which are diagrammatically shown in Fig. 1 have been given the same reference characters as assigned to the represented parts of the specific construction already described, and obviously this track circuit current flows through windings 13 and 14 to attract and hold the armature 17 in its upper position, which current is adjusted by the variable resistor R to provide a predetermined desired 40 value of magnetomotive force which is sufficient to easily attract the armature 17 under normal or average leakage current through the ballast separating the rails T when not shunted by a train.

The manually adjusting arm 48 (not shown in Fig. 1) is now also adjusted to allow a flux value 50 in the armature 17 in response to this adjusted value of magnetomotive force, which produces a tractive force reliably retaining the armature 17 in its attracted position, but which permits the reduction in magnetomotive force effected by the 55 train shunt obtaining on the particular track section to reduce this flux value considerably below the value at which the relay armature 17 is found to drop away. In other words, the means for manually adjusting the air gap normally separating the armature 17 from the pole pieces 9 and 10 provides a simple and convenient means for adjusting the release value of the relay armature 60 without affecting the pick-up value.

When the inter-rail leakage current changes in 65 the track circuit of Fig. 1, due, for example, to weather changes, the changes in relay energization resulting therefrom occur gradually and the armature 37 rotates in a corresponding direction accordingly, thereby increasing or decreasing the 70 reluctance of the magnetic circuit in inverse proportion to the change in magnetomotive force produced by the change in energization to maintain a constant flux, and obviously a constant tractive force acting on the armature 17 in the manner 75 previously described. However, when the train

enters the track section to shunt the rails T, the energization of the relay coils 13 and 14 is quickly decreased, and inasmuch as the compensating armature 37 is retarded by the washers 43 (not shown in Fig. 1) the flux decreases in the armature 17 beyond a point where the retaining force is overcome by the gravitational biasing force and the armature 17 immediately drops away. The dropping of the armature 17 then engages the arm 44 with the sector 40 and prevents movement of the compensating armature 37 as long as the track rails T are shunted. It may be mentioned that this means for preventing the operation of the compensating armature 37 while the armature 17 is released may be omitted from the present devices and yet retain the most desirable operating characteristics, but in order to prevent unnecessary operation of armature 37 as previously outlined, its incorporation is considered advantageous.

An air gap compensating means is thus provided which operates to maintain a constant force retaining the armature 17 in its attracted position regardless of various gradual changes in the energization of the relay. This arrangement then 25 insures that the relay armature releases in response to a rapid reduction of energization with the same certainty regardless of the degree of energization of the relay coils which had prevailed before the rapid energy reduction.

In the modified form of the present invention shown in Fig. 7 and Fig. 8, substantially the same main magnetic structure has been shown in order to simplify the disclosure, but the mechanical construction of the compensating means is entirely 35 different although the principle of operation is substantially the same. The specific construction in Fig. 7 and Fig. 8 comprises a horizontal magnetic shaft 55 rotatably supported in front of the pole pieces 9 and 10 by two brackets 56 fixed to 40 the top plate 11 by bolts 57 and nuts 58, which brackets 56 carry threaded pins 59 having reduced ends entering holes in each end of the shaft 55, as shown in Fig. 8. The pins 59 being threaded into the brackets 56 may be adjusted 45 longitudinally to permit free rotation of the shaft 55 but substantially no longitudinal movement, and lock nuts 60 threaded on the pins 59 may be employed to hold the pins 59 in such adjusted 50 positions.

The ends of the magnetic shaft 55 carry magnetic vanes 62 and 63 clamped on reduced diameter ends thereof by nuts 64, and these vanes are spaced to magnetically coact with the outer vertical edges of the pole pieces 9 and 10 respectively through small separating air gaps. The armature 17 in this embodiment is considerably shorter than the spacing of the vanes 62 and 63, both for the purpose of clearing these vanes and to minimize the magnetic effect between the vanes and the armature. A cam member 65 is suitably attached to the center of the shaft 55 which cam 65 engages an enlarged head of a screw 66 threaded into a forwardly extending arm 67 suitably attached to the armature 17, the 60 screw 66 being locked in position by a nut 68.

A coil spring 69 is provided around the shaft 55 with a center loop engaging the lower edge of a forwardly extending arm 70 on the cam member 65, and the extreme outer ends of the spring 70 70 69 extend over the top of the shaft 55 toward the pole pieces 9 and 10 with upwardly bent ends entering holes (not shown) in the top plate 11. The shaft 55 is thus biased in a counter-clockwise direction of rotation, which direction of ro- 75

tation is limited by a screw 71 threaded through the top plate 11 and locked by a nut 72 so that its lower end may engage the cam arm 70 when operated to its extreme upper position.

5 The manner in which the vanes 62 and 63 contact with the respective pole pieces 9 and 10 may be clearly seen from Fig. 7, or that is, these vanes are magnetically attracted upwardly against the force of the spring 69 to register more of their 10 vertical surfaces with the outer surfaces of their respective pole pieces as the energization of coils 13 and 14 is increased, thereby rotating the shaft 55 in a clockwise direction in accordance with the degree of energization of the relay. The cam 15 15 65 is arranged as shown in Fig. 7 so that this clockwise rotation engages portions on its periphery with the head of the screw 66 which are of continuously increasing radii, thus forcing the armature 17 away from the pole pieces 9 and 10. 20 The profile of the cam 65 is then arranged to at all times enforce an air gap between the armature 17 and the pole pieces 9 and 10 which is in inverse proportion to the magnetomotive force prevailing between the pole pieces.

25 In order to retard the operation of the vanes in response to an abrupt change in magnetomotive force, two sleeves 73 are provided on the shaft 55 between the cam member 65 and the two vanes 62 and 63, which sleeves are of a non-magnetic current-conducting material. These sleeves 30 35 73 then act as a flux retarding choke means which opposes a rapid change in the value of flux flowing from one vane to the other through the shaft 55, but are comparatively ineffective to retard gradual flux changes.

35 The construction of the relay to which the modified compensating means shown in Fig. 7 and Fig. 8 has been applied has been considered to be the same as previously described in connection with the other embodiments, but some 40 45 modifications are obviously necessary such as the U-shaped armature-supporting bracket 18 (not shown in Fig. 8), which in this case must be made wider in order to clear the vanes 62 and 63, and also the inner vertical edges of the pole pieces 9 and 10 are preferably plain in Fig. 7 and Fig. 8 instead of concave as shown in Fig. 4.

50 Suitable contacts are of course to be operated by the armature 17 and such contacts are usually sufficiently flexed when engaging the associated upper fixed contacts so that the variations in position of the armature 17 as caused by the compensating means will not affect the resistance of the electrical circuit therethrough. 55 The edge of the cam 65 which contacts with the head of the screw 66 has been rounded as shown to reduce the frictional resistance to the rotation thereof to a minimum.

60 The operation of the modified form of the present invention illustrated in Fig. 7 and Fig. 8 when applied to the railway track circuit of Fig. 1 is substantially the same as the other forms, or that is, when the track circuit current is adjusted by the variable resistor R to a value, which 65 by flowing through the windings 13 and 14 produce a flux which reliably attracts the armature 17 from its released position, the air gap between the pole pieces and the armature when in its attracted position may then be adjusted by the screw 66, under conditions providing a normal or 70 average inter-rail leakage current, to produce a flux value which affords a reliable armature release in response to a train shunt. The shaft 55 is of course assuming an intermediate position when the adjustment of the screw 66 is be-

ing made because the normal degree of energization of coils 13 and 14 produces a flux flowing from one pole piece, through the associated vane, through the shaft 55, and to the other pole pieces through the other vane, which flux produces an upward attraction of the vanes 62 and 63 which is equally opposed by the spring 69 only at an intermediate position of the shaft 55.

75 The shaft 55 will now be rotated in either direction by an upward or downward movement of the vanes 62 and 63 in accordance with the gradual changes in the energization of coils 13 and 14 which may be caused by natural changes in the inter-rail leakage current. The rotation of shaft 55 then varies the reluctance of the 15 magnetic circuit by the cam 65 in such a proportion to the changes in the energization of coils 13 and 14 that the flux in the armature 17 is maintained at the value selected by the screw 66.

20 However when a train enters the track section, the energization of coils 13 and 14 is quickly decreased, but due to the flux retarding sleeves 73, the flux in the shaft 55 does not immediately decrease proportionally, and consequently the reluctance of the magnetic circuit is not effectively changed by a rotation of the cam 65 before the armature 17 drops away. A means for preventing a movement of the air gap regulating means while the armature 17 is dropped away has not been shown in this modified form, but it is 30 35 obvious that an arm operated by the armature 17, as shown in Fig. 3, could operate in a similar manner to engage an extension of the vanes 62 and 63, for example, and thus prevent rotation of the shaft 55 while the armature 17 is in its 35 released position.

40 In all the forms of the present disclosure, it has been considered that the variations in the amount of flux passing through the compensating magnetic structures according to their rotated positions do not materially affect the amount of flux passing through the armature 17, except due to the effected change in air gap, but it is obvious that the flux path through the armature 37 or the shaft 55 is in multiple with 45 the path through the armature 17, and in some cases, it may be found that a change in position of the compensating means materially affects the armature 17 apart from the air gap variation. However, it is contemplated that in this case, 50 55 the only result would be an over-compensation which could be rectified by a change in tension of the springs 38 or 69.

60 A simple and compact relay has thus been provided which is particularly adaptable to normally energized circuits in which it is desirable to detect, with great certainty, an abrupt reduction in the energization thereof. Many of such normally energized circuits are materially affected by changes in natural conditions, such as 65 gradual variations in the electromotive force of the source of energy, and changes in the inter-rail leakage current in track circuits caused by varying weather conditions, and the present relay provides a means for detecting an abrupt reduction in the energization of such a circuit with equal certainty regardless of the natural conditions which had prevailed previous to such abrupt reduction. The manner in which the above operation is accomplished is particularly reliable 70 and advantageous because the reliability of the energizing circuit is in no way impaired by the use of automatically variable resistors or the like, but rather a simple and positive means has been employed to regulate the reluctance of the relay's 75

magnetic circuit, thus preventing continued operation from altering the electrical characteristics of the energizing circuit in any manner.

The above rather specific description of the 5 embodiments of the present invention is given solely by the way of example, and is not intended, in any manner whatsoever, in a limiting sense. It is also to be understood that various modifications, adaptations and alterations may be applied to meet the requirements of practice, without in any manner departing from the spirit or scope of the present invention, except as limited by the appended claims.

Having thus described my invention, what I 15 claim is:

1. A relay having in combination, a U-shaped magnetic structure, windings on the magnetic structure, a main armature attracted to a position magnetically joining the ends of the U-shaped magnetic structure when current above 20 a predetermined value flows in the windings, a threaded shaft interposed between the armature and the magnetic structure whereby the proximity of the armature to the ends of the magnetic structure may be determined in accordance with 25 the rotated position of the threaded shaft, a magnetic member carried by the threaded shaft and coacting with the ends of the U-shaped magnetic structure whereby to rotate the shaft, 30 and an arm on the armature operable to prevent rotation of the shaft while the armature is in its unattracted position.

2. In a relay of the class wherein an armature is moved toward an electromagnet in response 35 to a degree of energization of the electromagnet which is above a predetermined value and said armature is moved away from the electromagnet by a biasing means when the degree of energization of the electromagnet falls below said predetermined value, the combination of, regulating means variably limiting the distance of movement of the armature toward the electromagnet in accordance with the degree of energization of the electromagnet, and means retarding the response of the regulating means to abrupt changes 40 in the degree of energization of the electromagnet.

3. In a relay of the class wherein an armature is held toward an electromagnet in response 50 to a degree of energization of the electromagnet which is above a predetermined value and said armature is moved away from the electromagnet by a biasing means when the degree of energization of the electromagnet falls below said predetermined value, the combination of regulating means variably limiting the movement of the armature toward the electromagnet in accordance with the degree of energization of the electromagnet, means retarding the response of 55 the regulating means to abrupt changes in the degree of energization of the electromagnet, and locking means preventing operation of the regulating means while the armature is operated away from the electromagnet by the biasing means.

4. In a relay, an electromagnet having two 60 extending pole pieces, an armature operable toward the pole pieces when current above a predetermined value flows in the electromagnet and operable away from the pole pieces by gravitational force when said current falls below said predetermined value, and means coacting with the pole pieces for variably separating the armature from the pole pieces in accordance with the 70 amount of current in the electromagnets, the

operation of said means being delayed in response to changes in current in the electromagnet which occur abruptly.

5. In a relay, an electromagnet having spaced 5 extending pole pieces, a contact-operating armature positioned to magnetically connect the pole pieces and to vary the reluctance of the magnetic circuit of the electromagnet in accordance with its proximity to the pole pieces, a rotatable armature positioned between the pole pieces and 10 rotatable against a biasing spring to various positions in accordance with the magnetomotive force existing between the pole pieces, and means enforcing a separation of the contact operating armature from the pole pieces in accordance with 15 the position of the rotatable armature whereby the magnetic flux in the contact operating armature is maintained a constant value regardless of changes in the magnetomotive force of the electromagnet.

6. In a relay having electromagnetic structure including windings about spaced magnetic cores, the cores being magnetically joined at their upper ends and having enlarged pole pieces at their lower ends attached beneath a non-magnetic top 25 plate; an armature operable toward and away from the lower surface of the pole pieces, a vertical shaft between the pole pieces and having a lower end engaging the armature with an upper end threaded into a holding member manually 30 rotatable within the top plate, a magnetic member attached to the shaft and coacting with the vertical edges of the pole pieces in a manner to magnetically effect rotation of the shaft in one direction, a spiral spring acting in opposition to the magnetic rotation of the shaft, a horizontal sector attached to the shaft, and an arm operated by the armature toward the edge of the sector when the armature is operated away from the pole pieces.

7. In a relay having electromagnetic structure including windings about spaced magnetic cores, the cores being magnetically joined at their upper ends and having enlarged pole pieces at their lower ends attached beneath a non-magnetic top plate; an armature operable toward and away from the lower surface of the pole pieces, a vertical shaft between the pole pieces and having a lower end engaging the armature with an upper end threaded into a holding member manually 45 rotatable within the top plate, a magnetic member attached to the shaft and coacting with the vertical edges of the pole pieces, a winding on the magnetic member arranged when energized to magnetically effect rotation of the shaft in one direction, a spiral spring acting in opposition to the magnetic rotation of the shaft, a horizontal sector attached to the shaft, and an arm operated by the armature toward the edge of the sector 50 when the armature is operated away from the pole pieces.

8. In a relay having an electromagnetic structure including windings about spaced magnetic cores, the cores being magnetically joined at their upper ends and having enlarged pole pieces 55 at their lower ends attached beneath a non-magnetic top plate; an armature operable toward and away from the lower surface of the pole pieces, a magnetic shaft rotatably carried by the top plate, rotatory biasing means acting on the shaft, magnetic vanes fixed to the ends of the shaft and coacting with the outer vertical surfaces of the pole pieces whereby the shaft is rotated in opposition to the rotatory biasing means 60 in accordance with the magnetomotive force of the electromagnet.

taining between the pole pieces, a cam operating to enforce a separation of the armature from the pole pieces in accordance with the rotated position of the shaft, and a non-magnetic current-conducting sleeve on the shaft whereby to retard the rotation of the shaft in response to an abrupt change in the magnetomotive force between the pole pieces.

9. In a relay wherein an electromagnet is normally energized to attract an armature toward pole pieces of the electromagnet, the combination of a magnetic shaft rotatably held in a definite relation to the pole pieces, magnetic vanes on the ends of the shaft coating with the pole pieces 10 in a manner to rotate the shaft, biasing means opposing such rotation of the shaft whereby the shaft is rotated to various positions depending on the strength of the magnetomotive force between the pole pieces, means regarding the rotation of 15 the shaft in response to an abrupt change in the strength of said magnetomotive force, and cam means on the shaft operating on the armature to thereby regulate the separation of the armature from the pole pieces in inverse proportion to 20 gradual changes in the strength of said magnetomotive force.

10. In a relay wherein an electromagnet is normally energized to attract an armature toward pole pieces of the electromagnet, the combination 30 of a magnetic shaft rotatably held in a definite relation to the pole pieces, magnetic vanes on the ends of the shaft coating with the pole pieces in a manner to rotate the shaft, biasing means opposing such rotation of the shaft whereby the 35 shaft is rotated to various positions depending on the strength of the magnetomotive force between the pole pieces, means retarding the rotation of the shaft in response to an abrupt change in the strength of said magnetomotive force, cam means 40 on the shaft operating on the armature to thereby regulate the separation of the armature from the pole pieces in inverse proportion to gradual changes in the strength of said magnetomotive force, and means for manually adjusting the 45 separation of the armature from the pole pieces which permits subsequent regulation thereof by the cam means.

11. In a relay, two vertical magnetic cores joined at one end and having enlarged pole pieces 50 at the other ends, a non-magnetic member holding the cores, windings on the cores, an armature operable toward or away from the pole pieces in accordance with the degree of energization of the windings, a manually rotatable member 55 in the core holding member, a shaft threaded into the manually rotatable member and engaging the armature when operated toward the pole pieces, and means for automatically rotating the shaft in accordance with gradual changes in the 60 degree of energization of the windings.

12. A relay having in combination, an electromagnet having an incomplete magnetic core, a contact operating armature operable to a position completing the core of the electromagnet, and 65 magnetic means automatically providing a length of air gap between the armature and the core of the electromagnet which is in inverse proportion to the degree of energization of the electromagnet, whereby to maintain a constant value 70 of magnetic flux in the armature regardless of gradual changes in the degree of energization of the electromagnet.

13. In a normally energized track circuit, a relay energized by the track circuit current to hold a contact-operating armature in an attract-

ed position when the track circuit is unshunted, a compensating armature in the relay movable to various positions in accordance with the degree of energization of the relay, means operated by the compensating armature to move the contact-operating armature in a manner to maintain a constant flux in the contact-operating armature regardless of gradual changes in the normal energization of the relay, and means retarding the response of the compensating armature to an abrupt decrease in energization of the relay, whereby to permit the contact-operating armature to drop away in response to a shunt on the track circuit before the compensating armature effectively moves in response to such shunt. 15

14. In a track circuit, a track relay, a first armature in the track relay attracted or released in accordance with the unshunted or shunted condition of the track circuit, and a second armature in the track relay regulating the attracted position of the first armature in accordance with gradual changes in the degree of energization of the track relay when unshunted, whereby to permit the release of the first armature in response to a shunt on the track circuit 20 with equal certainty regardless of the prevailing ballast condition in the track circuit.

15. In a track relay, a first armature attracted or released in accordance with abrupt changes in the degree of energization of the relay, and a second armature regulating the attracted position of the first armature to maintain a constant flux density in the first armature regardless of gradual changes in the degree of energization of the relay. 30

16. In a track relay, an electro-magnet having extending pole pieces, an armature operable toward said pole pieces when current above a predetermined value flows in the electro-magnet and operable away from the pole pieces by gravitational force when said current falls to a predetermined lower value, slow acting adjusting means for variably separating the armature from the pole pieces when in its attracted position in accordance with gradual changes in the potential 40 across said electro-magnet, and means for locking said adjusting means upon dropping of said armature.

17. In a relay, a magnetic core structure terminating in two pole pieces, a winding mounted 50 on the core, an armature biased to a position away from the pole pieces and movable toward said pole pieces in response to magnetic flux created by current supplied to the winding, a magnetic shunt path including a magnetizable member movable to different positions relative to said pole pieces for regulating the flux which passes through the armature in response to variations in the magnitude of the current supplied to the winding, and means controlled in 60 part by said armature for governing the position of said member. 55

18. In a relay, a magnetic core structure terminating in two pole pieces, a winding mounted on said core, an armature mounted for movement relative to said pole pieces in response to magnetic flux created by current supplied to said winding, an auxiliary magnetizable member mounted for movement relative to said pole pieces in response to such magnetic flux for regulating 70 the flux through the armature in response to variations in the current strength supplied to the winding, a biasing device for governing the position of said member when influenced by the flux, and means controlled by said armature operative 75

when the armature is released in response to deenergizing the winding to retain said auxiliary member at the position to which it was moved by the magnetic flux.

5. 19. In combination, a section of railway track, a source of current connected across the rails of said section, an electromagnet receiving current from said rails and having an armature adjusted for operation when the magnetic flux acting thereon is that created by a predetermined value of current, a movable magnetizable member operable to different positions relative to the core structure of the electromagnet for regulating the flux which passes through said armature to reduce in the armature the flux created by currents greater than said predetermined value, and means controlled in part by the position of said armature for governing the position of said member.
10. 20. In a relay, a magnetic core structure terminating in two pole pieces, a winding mounted on said core, an armature mounted for movement relative to said pole pieces in response to magnetic flux created by current supplied to said winding, a magnetic shunt path including a magnetizable member mounted for magnetic relationship with said pole pieces for regulating the magnetic flux through the armature when current above a predetermined value is supplied to the winding, and a short-circuited winding mounted on the shunt path for delaying the dying away and the building up of flux through said shunt path.
15. 21. In combination, a section of railway track, a source of current connected across the rails of said section, a track relay receiving current from said rails and adjusted for release of its armature at a predetermined value of current, a movable magnetizable member mounted for movement relative to the pole pieces of the relay by flux flowing in multiple with said armature, and means to associate movement of the member with movement of the armature whereby a gradual change in the ballast resistance of the section automatically changes the setting of the member but a sudden decrease in the energizing current to release the armature causes the member to be retained in its former setting.
20. 22. A relay of the direct current tractive type for use with track circuits on railroads comprising, a magnetic core structure forming two spaced pole pieces, a winding on said core structure, a main contact operating armature biased

for movement away from said pole pieces and attracted toward said pole pieces by magnetic flux created by current flowing in said winding, an auxiliary movable armature disposed in a magnetic path in shunt with said main armature and responding to variations in the current in said winding, spring means for biasing said auxiliary armature with a force varying with its position toward a position for maximum reluctance of said shunt path, said auxiliary armature assuming different positions in its magnetic shunt path dependent upon the strength of the current in said winding, and means actuated by movement of said main armature to its retracted position for retaining said auxiliary armature in its then existing position.

23. A relay of the direct current tractive type for use on railroads comprising, a core structure and a winding for attracting a biased movable armature to open and close contacts, a magnetic movable member disposed in a magnetic flux path in shunt with said armature, spring means for biasing said member to a position for the maximum reluctance of said shunt path, said member being moved in opposition to said spring means by variations in the current flowing in said winding to different positions dependent upon the magnitude of such current, means associated with said movable member for delaying a change in its position in response to a change in the current in said winding, and means responding to the movement of said armature to its retracted position for retaining said member in the position existing at the time said armature assumes its retracted position.

24. In a relay of the type described, a magnetic core structure terminating in two spaced pole pieces, a winding on said core structure, a main movable armature attracted toward said pole pieces by the magnetic flux in said core structure produced by current flowing in said winding, means including a biased movable auxiliary armature disposed in a magnetic flux path in shunt with said main armature for varying the flux passing through said main armature depending upon the magnitude of current in said winding, a short-circuited winding associated with said shunt path for retarding a change of flux therein, and means actuated by movement of said main armature to its retracted position for holding said auxiliary armature in its then existing position.

EDWIN O. BLODGETT.
